(57) CLAIM

The ornamental design for a hat with a ponytail hole, as shown and described.

DESCRIPTION

FIG. 1 is a front perspective view of a first embodiment of a hat with a ponytail hole with a middle portion in an open position;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof;

FIG. 7 is a bottom plan view thereof;

FIG. 8 is a front perspective view thereof of the hat with a ponytail hole with the middle portion in a closed position;

FIG. 9 is a front perspective view of a second embodiment of a hat with a ponytail hole with a middle portion in an open position;

FIG. 10 is a front elevational view thereof;

FIG. 11 is a rear elevational view thereof;

FIG. 12 is a first side elevational view thereof;

FIG. 13 is a second side elevational view thereof;

FIG. 14 is a top plan view thereof;

FIG. 15 is a bottom plan view thereof; and,

FIG. 16 is a front perspective view thereof of the hat with a ponytail hole with the middle portion in a closed position.

The broken lines shown in the figures depict portions of the hat with a ponytail hole that form no part of the claimed design.

1 Claim, 16 Drawing Sheets
